(57) **CLAIM**

I claim the ornamental design for a cable organizer, as shown and described.

DESCRIPTION

FIG. 1 is a perspective view of the cable organizer;
 FIG. 2 is a bottom view of the cable organizer;
 FIG. 3 is a right side view of the cable organizer;
 FIG. 4 is a left side view of the cable organizer;
 FIG. 5 is a top view of the cable organizer;
 FIG. 6 is a front view of the cable organizer; and,
 FIG. 7 is a rear view of the cable organizer.

The broken lines represent environment that forms no part of the claim.
